UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING LOOSE MATERIALS.

Application filed July 15, 1925. Serial No. 43,671.

This invention relates to apparatus for handling loose material in mines, and more particularly to the type of apparatus disclosed in my prior application bearing Serial Number 638,232, filed May 11, 1923, which apparatus includes a draft operated scraper, and a mobile head frame capable of being readily moved from place to place and adapted to provide a lateral support for the scraper so as to direct it into a pile of loose material while it is gathering its load, and other guiding devices are provided for directing the movement of the scraper in predetermined angular courses toward and away from the point of discharge.

The principal object of this invention is to provide means in cooperation with the moving head frame whereby the scraper may be turned and its direction of movement controlled during its reciprocal movement between the head frame and the point of discharge.

The invention may be best understood by reference to the accompanying drawings illustrating one form in which it may be embodied, in which:

Figure 1 is a plan view of a mobile head frame including a portion of my improved scraper controlling apparatus;

Figure 2 is a vertical section taken longitudinally of the machine shown in Figure 1;

Figure 3 is an enlarged sectional view taken on line 3—3 of Figure 1;

Figure 4 is a sectional view taken on line 4—4 of Figure 1;

Figure 5 is a view showing the relation of the scraper controlling apparatus in one position thereof;

Figure 6 is a view similar to Figure 5 but showing the controlling apparatus in another position;

Figure 7 is a detail of the power connection between the tail rope drum and the scraper driving ring;

Figures 8, 9 and 10 are plan views illustrating a typical installation of the apparatus in a mine room; and

Figure 11 is another view of a mine room showing one arrangement of the control ropes for the scraper.

The invention is particularly adapted for

controlling the movement of a scraper loader as used in the room and pillar system of mining or in other similar systems wherein it is desirable to change the course of movement of the scraper intermediate the position where the load is gathered and its point of discharge. For instance, when used in the room and pillar system of mining, as shown in the diagrams, the scraper gathers in its load adjacent the working face 2 at one end of a mine room 1 and its path of movement is then changed as it approaches one side 3 of the room and is then withdrawn in a path substantially parallel with said side wall or rib 3. One of the problems heretofore encountered in the operation of scraper loaders is to provide means for controlling the movement of the scraper during its turning operation so that it may be quickly turned without danger of upsetting the scraper or producing such strains and shocks on the controlling apparatus fixed in the mine as to require excessively cumbersome holding devices. It will be understood that in mining operations such as herein contemplated, it is highly desirable to provide controlling devices having minimum weight, and requiring minimum labor in operation and in transportation thereof from place to place.

My invention contemplates the use of a scraper 15, herein shown as bottomless, and provided with a head rope 16 and a tail rope 17 for reciprocal operation. In conjunction with the scraper I provide a head frame 4 arranged in position to provide lateral bearing for the scraper whereby the latter is directed into the pile of loose material to gather the same. Such a head frame is broadly disclosed in my prior application bearing Serial Number 638,232, filed May 11, 1923.

The present invention also contemplates the provision of a controlling device for assisting in the turning movement of the scraper, this device being operable under the power of the motor devices on the head frame and in the present instance comprising a rotatable power drum 140 associated with a control rope 141 and a sheave 150 at the far end thereof connected with the head rope 16. In order to understand the invention however, a brief description of the head

frame and its manner of cooperation with the draft ropes of the scraper will be first presented.

A main frame 10 is supported on a pair 5 of tractor wheels 12, 12, within the main frame, and a steering wheel 13, pivotally supported at the rear end of the frame to steer the apparatus. In the form shown the main frame comprises a forward end section 10 14 substantially circular in form and a rearwardly extending section 25 having a bracket 26 supporting the steering post 27 of the steering wheel 13. A steering handle 28 of any suitable form is connected to the upper 15 end of the steering post 27.

Power devices are mounted on the head frame for positively moving the scraper in its gathering or digging movement about the frame, these power devices preferably being 20 operable and controllable independently of the head rope. In the form shown this scraper moving mechanism includes an arm 30, and a projection 34, both extending laterally from the head frame and carried 25 on an annular driving ring 33 mounted concentric with the circular head frame 14. The arm 30 is provided with a bearing shoe 31 adjacent its outer end for engaging the rear end of the scraper and also carries a guide or 30 sheave 32 for engaging the tail rope 17. The projection 34 is located forwardly of the arm 30, and adapted to engage a hooked portion 34^a at the forward end of the scraper, (see Figure 1).

35 Suitable gearing connections are provided between the prime mover comprising a motor 40 and the driving rings 33 so as to move the scraper at a relatively low speed about the head frame. In the form shown said 40 ring is adapted to be driven through the medium of the tail rope drum 18, and a ratchet device which provides a driving connection between the drum and ring whereby they are rotated in unison by power applied 45 on the drum.

The low speed connections to the drum 18 and driving ring 33 will now be described. The motor 40 on the head frame may be of any kind, as for instance, an electric motor 50 having a driving shaft 41, as shown in Figure 2. This shaft is provided with two driving pinions 42 and 43. The driving pinion 42 is meshed with the gear 44 associated with one member 45 of a double clutch mechanism 46. The driving pinion 43 is connected through the idler gear 47 with a gear 48 associated with another member 49 of the double clutch mechanism. These clutch members 55 45 and 49 are loosely mounted on a shaft 55 and are adapted to be selectively engaged by a pair of oppositely disposed cone clutch members 58, 59, feathered on the shaft 55 and movable in opposite directions to engage one or the other of said clutch members. 60 The clutch member 49, being driven through

the idler gear 47 as described, affords reversed movements of the two clutch members 45 and 49 respective to each other so as to drive the shaft 55 in opposite directions, as desired.

70 The low speed connection includes either of the coacting clutch members of the double clutch mechanism 46 just described, the shaft 55 extending rearwardly from this double clutch mechanism having a worm 77 thereon 75 engaging a coacting worm gear 78 on a horizontal shaft 79. A gear 80 is keyed on the latter shaft and is engaged with a gear 81 on the parallel shaft 82. The gear 81 is provided with sliding clutch members 84, 84 extending therethrough, and movable by a shifter member 85 into driving engagement with a beveled pinion 86. Said pinion is meshed with a beveled gear 70 carrying a spur gear 72 meshed with a toothed periphery 73 of the upper drum flange.

75 The ratchet device connecting rope drum 18 with arm 30 may be of any suitable construction. For example, a pawl 90 is pivotally mounted on said arm adjacent the lower drum flange 36 and is adapted to engage in a series of notches 91, 91, formed about said flange. The pawl is under tension of a suitable spring 92. The arrangement is such that when the tail rope drum is driven at low speed in a direction to unwind the rope, the pawl 90 engages one of the notches 91, and the driving ring 33, which carries arm 30 and retaining member 34 will be rotated in 80 unison with the drum to advance the scraper about the head frame. Simultaneously, the tail rope will be unwound from the drum. The scraper is thus positively propelled at low speed, and by reason of the reduction gearing, the power applied to the driving ring 33 is correspondingly increased so as to 85 force the scraper into the loose material during its movement about the head frame.

85 In the form shown, a high speed driving connection to the tail rope drum 18 is also provided from shaft 55 through the following mechanism. A gear 65 keyed on shaft 55 is meshed with a gear 66 keyed on a parallel shaft 67. Sliding clutch 68 is feathered on the latter shaft, and is adapted in 90 one position to operatively engage a bevel pinion 69 meshed with the beveled gear 70. This last named gear also comprises a part of the low speed connection, before described, and from this point on both high and low speed connections to the drum are 95 the same, including the upright shaft 71 and spur gear 72 meshed with toothed flange 73 of the tail rope drum 18. By 100 means of the high speed gearing just described the drum 18 may be driven in a direction to wind in the tail rope at a relatively high speed after the scraper has been unloaded and is being returned empty to 105 a loading position at the head frame.

The power connections for propelling the head frame need not be described in detail as they form no part of the present invention.

- 5 Having now described the construction of the head frame the details of my improved controlling mechanism forming the subject matter of the present invention will now be described in connection therewith.
- 10 A second rope drum 140 is mounted on the head frame and adapted to have a control rope 141 wound thereon. This control rope is adapted to extend from the drum to a fixed guide device located at a point remote
- 15 from the head frame where it is desired to change the course of movement of the scraper. In the diagrams shown in Figures 8 to 11 a typical arrangement of the head frame and control rope is illustrated
- 20 as applied to the room and pillar system of mining. In these figures a room 1 is being formed by advancing a working face 2 by successively dislodging and breaking down said working face into a pile
- 25 of loose material as indicated at 125 and loading out each successive pile by means of the scraper 15. As is often the case in loading out a room it is desirable to confine the path of movement of the scraper
- 30 along one side or wall 3 of the room since the main portion of the room may be occupied by props or by waste materials. Accordingly, the path of movement of the scraper must be confined within somewhat
- 35 limited range along the working face and then at an angle thereto along the side wall 3 toward the entrance of the room (not shown). It will be understood that the head rope 16 is attached to a hoist or winding
- 40 device suitably arranged at or near the entrance of the mine room and said head rope being trained over suitable guides to direct the movement of the scraper to a desired point of unloading as for instance into mine
- 45 cars at the room entrance. The arrangement of the head rope hoist, as well as the unloading or discharging apparatus need not be illustrated herein, as they form no part of the present invention.
- 50 Referring further to the control line 141 it will be seen that this line extends to the corner of a room formed by cutting of the side wall 3 and the working face 2 in which corner the scraper is turned reciprocably in
- 55 its movement. A preferable arrangement of the guiding devices for this corner comprises a pair of sheaves 146, 147, spaced vertically on a jack 148 which may be of the usual form, the upper sheave 146 being raised above the level of the ground sufficiently to permit the scraper 15 to pass thereunder, as clearly shown in Figure 11. As shown herein, the control line 141 is also trained about a guide 149 arranged at the
- 60 forward end of the head frame 4 although
- it is obvious that this line may also be trained directly off the winding drum 140 if desired. The free end of the control line 141 is provided with a guide sheave 150 through which the head rope 16 is trained. 70 This guide sheave has permanent connection with the head rope in all positions of the scraper.
- 75 A deflector guide 155 is preferably positioned a sufficient distance from the working face 2 and the side wall 3 to permit the scraper to be passed thereabout as shown in Figures 8 to 10. This deflector guide serves to confine the position of the draft ropes along the path of movement of the scraper, 80 as will hereinafter more fully appear.
- 85 Referring now to the means for driving and controlling the control drum 140 it will be seen that this drum is rotatably mounted on a stud 160 which in turn is mounted eccentrically on an upright shaft 161 on the top of the frame portion 25. The shaft 71, power driven through mechanism as heretofore set forth, extends upwardly within the periphery of the drum and is provided with a friction pulley 162 adapted to having driving engagement with the inner surface 163 of said drum. A control lever 164 is connected with the upper end of the stud 160 and extends rearwardly into position to be manually operated, as shown in Figure 1. A brake 165 is mounted on the frame 25 in position to engage an outer surface 166 of the drum. In Figures 5 and 6 it will be observed that by means of an eccentric 160 the drum 140 may be moved bodily into position to engage the brake 165 in one position of said handle, and as shown in Figure 6 the drum may be swung into another position to provide a driving engagement with the frictional drum 162. A third, or neutral position is also possible, in which the drum may rotate freely. 90

The use and operation of the apparatus above described is as follows:

The head frame 4 is moved into position adjacent the toe of the pile of loose material 125 to be removed or transported, as shown in Figure 8. The head rope 16 is connected with the winding engine (not shown) suitably located in the usual manner to move the scraper to the unloading position, as for instance at the entrance of the room. The scraper is pulled rearwardly to its initial loading position by means of the tail rope 17 until it engages the head frame 4 in a position shown in Figure 1 in which the rear end of the scraper is in supporting engagement with the arm 30. It will be understood that the tail rope 17 is wound on the tail rope drum 18 under power of the motor on the head frame. In the initial loading position shown in Figure 1 the open end of the scraper faces the pile of loose material. The driving ring 33 upon which the arm 30 is

carried is then driven through ratchet mechanism 90 in unison with the tail rope drum 18 so as to force the scraper into the pile of loose material as it moves forward about the 5 curved portion 14 of the head frame. During this loading movement of the scraper it is usually desirable to place a slight tension on the head rope 16 by means of the winding engine so as to take up the slack therein.

10 The control line 141 and sheave 150 are held in position by engaging the brake device on the winding drum 140 controlling the position of the head rope 16, as shown in Figure 8. It will be observed that the operating 15 mechanism for this control line drum is at the hand of the operator of the head frame and the position of the guide sheave 150 is within his vision so that said control line may be slackened or tightened at will by 20 manipulating the controlling devices on the winding drum 140. When the scraper is moved about the head frame into position substantially parallel with the working face 2 it is ready to be drawn out under tension of 25 the head rope 16. The scraper may then be moved at a relatively higher speed under power of the head rope hoist and accordingly the low speed gearing connections on the head frame are disconnected, thereby 30 permitting the tail rope drum 18 to rotate freely as the tail rope is paid out. The scraper is thus permitted to move along the working face toward the control sheave 150, the latter being held in the desired position 35 by means of the control rope 141. Under ordinary circumstances it is sufficient to hold the control rope stationary by means of the brake, but it may be varied at any time by slackening or tightening the control rope to 40 deflect the scraper slightly either toward or away from the working face 2. When the scraper approaches the side wall 3 however, it reaches a position where it may be turned about the deflector 155 and into a path parallel 45 with the side wall 3. This turning movement may be made slowly by gradually releasing the brake on control line drum 140 until the forward end of the scraper engages the guide 150 at the end of said control line.

50 The control rope 141 is then slackened entirely by freeing the brake on the rope drum 140 thereby permitting said control line to be paid out freely as the scraper advances along the side wall 3 of the room toward the entrance, as shown in Figure 9. The scraper 55 at this point has completed its turning movement and is being pulled out at high speed by means of the head rope 16, the guide rope 141 being paid out to follow the scraper in its outward journey. This forward movement is continued until the scraper reaches the room entrance or place where the material is to be unloaded therefrom in the usual manner.

60 65 The return movement of the scraper to its

initial position is a reverse of that already described, it being understood that the head frame may be advanced from time to time to gather a capacity load each trip as the loading operation proceeds. In the return movement however it is necessary to apply power to the winding drum 140 in the direction to wind up the control line 141 in approximately the same speed that the tail rope is wound in. This operation is illustrated in 70 Figure 10 in which the winding drum 140 is engaged with the friction pulley 162 to retrieve the control line 141. It will be observed that the control line 141 may be also utilized to draw the scraper laterally toward 75 the side wall as it approaches the deflector guide 155 thus avoiding contact with this member and also assist in the rearward turning movement of the scraper into a position to engage the head frame and take its initial 80 loading position in engagement therewith for the next cycle of loading operation.

85 From the above description it will be seen that I provide a combination of moving head frame and controlling device which may be readily controlled by a single operator, stationed in position to manipulate the scraper and changing its course of movement as occasion may arise during the loading operations. The loading operation may thus be 90 carried out in a manner far superior to any arrangement in which the controlling line 141 might be under the control of another operator positioned remote from the head frame, as for instance at the winding engine 95 in the entrance of the room. In the latter case it has been found practically impossible to provide the desired control for the scraper inasmuch as the rooms may be 100 feet, 200 feet, or more in depth and of course the loading operations are conducted in darkness except for the meager light supplied by the miners' lamps or the like. By means of the 100 single control the use of signals between the head frame operator and the hoisting engine operator is required only for the starting and stopping of the head rope. By virtue of the simple operation of the turning device it is possible to move the scraper continuously 105 from the time it leaves the head frame until it reaches the unloading position and also in its return movement.

110 Although I have shown and described one form in which my invention may be embodied, I do not wish to be understood as 115 limiting myself to the specific construction illustrated herein excepting as specifically limited in the appended claims. It will also be understood that the construction and arrangement of the various parts may vary 120 widely without departing from the spirit and scope of my invention.

125 I claim as my invention:

1. An apparatus for handling loose material comprising a scraper having a head and 130

tail rope, a movable head frame having a curved bearing surface adapted to provide lateral support for said scraper while gathering its load, power devices on said head frame, and a control line operable by said power devices and extending about fixed guide means into engagement with the head rope of the scraper.

2. An apparatus for handling loose material comprising a scraper having a head and tail rope, a movable head frame having a curved bearing surface adapted to provide lateral support for said scraper while gathering its load, power devices on said head frame, and a control line operable by said power devices and extending about fixed guide means into engagement with the head rope of the scraper, said control line having permanent connection with said head rope and movable therewith in all permissible positions thereof.

3. An apparatus for handling loose material comprising a scraper having a head and tail rope, a movable head frame having a curved bearing surface adapted to provide lateral support for said scraper while gathering its load, power devices on said head frame, a control line operable by said power devices and extending about fixed guide means into engagement with the head rope of the scraper, and a deflector guide adapted to be positioned at a point intermediate said fixed guide means and said head frame.

4. An apparatus for handling loose material comprising a scraper having a head and tail rope, a movable head frame having a curved bearing surface adapted to provide lateral support for said scraper while gath-

ering its load, power devices on said head frame for operating said tail rope, and a control line operable by said power devices independently of said tail rope and extending about fixed guide means into engagement with the head rope of the scraper.

5. An apparatus for handling loose material comprising a scraper having a head and tail rope, a movable head frame having a curved bearing surface adapted to provide lateral support for said scraper while gathering a load, power devices on said head frame, a control line connectable with said head rope, and a winding drum for said control line mounted on said head frame and operatively connected with said power devices thereon.

6. An apparatus for handling loose material comprising a scraper having a head and tail rope, a movable head frame having a curved bearing surface adapted to provide lateral support for said scraper while gathering a load, power devices on said head frame, a control line operable by said power devices, and fixed guide means comprising a pair of vertically spaced guides, one arranged near the mine floor and the other at a point above the mine floor and substantially above the top of the scraper whereby the control line extends from said head frame to said upper guide thence downwardly and around the lower guide and into engagement with said head rope.

Signed at Chicago, in the county of Cook and State of Illinois, this 15th day of June, A. D. 1925.

CHARLES E. DAVIS.
